ATTYS

UNITED STATES PATENT OFFICE.

HERMANN MÜLLER, OF LEIPZIG-GOHLIS, GERMANY.

ELECTRICAL SUSPENSION-RAILWAY.

1,074,807.

Specification of Letters Patent.

Patented Oct. 7, 1913.

Application filed February 7, 1906. Serial No. 300,003.

To all whom it may concern:

Be it known that I, HERMANN MÜLLER, engineer, residing at Leipzig-Gohlis, Germany, subject of the German Emperor, have 5 invented certain useful Improvements in Electrical Suspension - Railways, of which the following is a full and clear description.

The object of the present invention is to regulate the supply of current and the speed 10 of electrically driven cars for suspended railways. For this purpose I have divided the conductor line into sections or blocks. I further arrange two auxiliary lines which are likewise divided into blocks. These 15 blocks are connected by circuit changers, whereby separate circuits are formed in the wire system of the different blocks. The circuit changers may be single pole or double pole changers.

20 The arrangement is shown in the drawing, in which:

Figure 1 is a side view of a suspended railway with two cars on different sections of the track. Fig. 2 is a sketch of the 25 circuit changing for the arrangement shown in Fig. 1. Fig. 2^a is a vertical section through one of the switches; Fig. 2^b is a like section taken at right angles to Fig. 2^a; Fig. 2^c is a detailed diagrammatic view; Fig. 3 30 is a plan showing the invention applied to a switch; and Fig. 4 is a like view showing the invention applied to a crossing.

A and B are the cars for the suspended railway, C—C is the track for the cars, 35 D—D is the conductor line, E—E is the main supply line. The conductor line receives its current from the main supply line E—E. In Fig. 1 it is divided into sections 1—2, 3—4, 5—6, 7—8. The sections of the 40 auxiliary lines are 9—10, 9'—10', 11—12, 11'—12'. The single pole circuit changers F and G serve to form the circuits. Any car arriving on block 7—8, Fig. 2, receives current from the main supply line E—E. In Fig. 1 it is divided into sections 45 19—20 is hereby cut off from the current as 100 it received its current by way of F, 21, 22, G, 15, 16. The section 19—20 is now without current as long as the car B is on section 13—14. The car A arriving on section 19—20 toward the switch is now stopped, 105 as this section is without current. Only after the car B leaves section 13—14 and turns the circuit changer from 21 to 17 section 19—20 is again connected and car A can proceed. In passing the switch it turns 110

at 5. The car is now supplied with current at the whole section 6—5 and arriving at 5 it turns the circuit changer F automatically from 9' to 9 whereby the section 7—8 is again supplied with current by way of circuit changer F near 5, auxiliary line 9—10, circuit changer G at 7. In passing over from block 6—5 to 4—3 the car turns the circuit changer G at 4 from 12' to 12 and hereby disconnects the section 5—6. Block 60 5—6 is now without current. The next car arriving at 7, block 7—8 would be stopped in passing over to 6 as long as there is a car on block 3—4. Only after the first car leaves block 3—4 and arrives at block 1—2 block 65 3—4 is cut off from the current and block 5—6 is again supplied with current. The car A, Fig. 1, is shown in block 1—2 opposite a bin for the purpose of loading. The next car B arriving from section 5—6 at 70 section 3—4 cannot run into car A as block 3—4 is without current and the car B must stop at 4. Only after car A passes over to the next block and turns the circuit changer F at 1 the block 3—4 is again supplied with 75 current and car B can proceed. The switch changing mechanism is shown in detail in Figs. 2^a and 2^b and comprises a four armed member *a* having its shaft *a'* rotatably mounted in the switch casing F. The arms 80 extend into such position as to be struck by a part of the passing car, for example, a part of the trolley head, whereby the member *a* is rotated through an arc of 90°. The shaft *a'* is connected by gearing *d* and *e* with a 85 rotary switch member *b* having contacts which coöperate with the contact springs or terminals *f*.

In Fig. 3 the arrangement is shown for a main track C—C with a switch H—H. 95 The current for the wire system is supplied by the dynamo Y. The car B running on section 16—15 turns the circuit closer G from 22 to 18 on arriving at 15. The section 19—20 is hereby cut off from the current as 100 it received its current by way of F, 21, 22, G, 15, 16. The section 19—20 is now without current as long as the car B is on section 13—14. The car A arriving on section 19—20 toward the switch is now stopped, 105 as this section is without current. Only after the car B leaves section 13—14 and turns the circuit changer from 21 to 17 section 19—20 is again connected and car A can proceed. In passing the switch it turns 110

the circuit changers F at 26 and G at 27. The section 13—14 is then connected with the current again. Car B, which is stopped at section 13—14 while the car A passed the 5 switch first, is now allowed to follow. In case the cars A and B arrive at 20 and 15 both at the same time, car A turns the circuit changer F and cuts off the current from section 13—14 whereby car B must stop on 10 this section while car A passes the switch first.

Fig. 4 represents a crossing and the circuit changing for the same. The car B on section 32—31 turns the circuit changer G 15 from 33 to 34 on arriving at 31. The section 36—37 on line N—N is hereby cut off from the current. Car A arriving from 38 is stopped at 37 until car B passes 39 and turns the circuit changer F from 39 to 35. 20 If, on the other hand, the car A arrives on track J—J in the direction of 38—36 it turns the circuit changer G at 37 to 40, whereby the section 31—32 is cut off from the current until car A turns circuit changer F at 42 25 to 41 *i. e.* until it has passed the crossing.

The switch shown in Figs. 2^a and 2^b does not form a part of my invention. The

switch is only shown to make the invention clear.

What I claim is:

An electric suspension railway comprising a main supply wire, a trolley wire divided into sections, a pair of auxiliary train supply wires divided into corresponding sections, a pair of switches mechanically operated by 30 the running car, arranged at each of the division points of the sections and controlling the connections with the auxiliary train supply wires, one switch of each pair normally connecting the corresponding section of one auxiliary wire with the main supply wire and one switch of another pair normally connecting said section of auxiliary wire with the trolley section to the rear of 40 said section of auxiliary wire whereby under 45 normal conditions this section of trolley wire is energized.

In witness whereof I have signed this specification in the presence of two witnesses.

HERMANN MÜLLER.

Witnesses:

RUDOLPH FRICKE,
KARL STUITZIG.
